US00D523908S

(12) **United States Design Patent** (10) **Patent No.:** **US D523,908 S**
Hedrick et al. (45) **Date of Patent:** **** Jun. 27, 2006**

(54) **GAMING DEVICE DISPLAY**

(75) Inventors: **Joseph R. Hedrick**, Reno, NV (US);
Christen Gadda, Las Vegas, NV (US)

(73) Assignee: **IGT**, Reno, NV (US)

(**) Term: **14 Years**

(21) Appl. No.: **29/212,956**

(22) Filed: **Sep. 10, 2004**

(51) **LOC (8) Cl.** **21-03**

(52) **U.S. Cl.** **D21/370**; D21/385; D11/163

(58) **Field of Classification Search** D11/163;
D21/325, 329, 369-371, 374,385, 440; 273/138.1;
463/16-17, 20, 25, 42, 46-47

See application file for complete search history.

(57) **CLAIM**

The ornamental design for a gaming device display, as shown and described.

DESCRIPTION

FIG. 1 is a perspective view of a gaming device display of our new design;

FIG. 2 illustrates a front elevation view thereof;

FIG. 3 illustrates a left side elevation view thereof, the right side being the mirror image thereof; and,

FIG. 4 illustrates a plan view thereof.

Those portions of the gaming device display shown in phantom in each of the figures are not part of the design sought to be patented and are provided for environmental purposes only.
